UNITED STATES PATENT OFFICE.

JASPER J. WALK, OF OAKLAND, CALIFORNIA.

ROTATING INTERNAL-COMBUSTION ENGINE.

1,344,158.

Specification of Letters Patent. Patented June 22, 1920.

Application filed May 28, 1919. Serial No. 300,301.

To all whom it may concern:

Be it known that I, JASPER J. WALK, a citizen of the United States, residing at Oakland, in the county of Alameda and State of California, have invented new and useful Improvements in Rotating Internal-Combustion Engines, of which the following is a specification.

This invention relates to an internal combustion engine and especially to an engine of the rotating type.

One of the objects of the present invention is to provide a compact, light-weight, internal combustion engine of the rotating type, in which both the cylinders and shaft revolve and which, while adapted to operate on the two-cycle principle, is in this instance particularly constructed for four-cycle operation.

Another object of the invention is to provide an engine of the character described, in which the pistons during their entire stroke, travel on a line substantially at right angles to the cranks, thus eliminating dead centers and furthermore obtaining a constant maximum leverage during the entire compression and working stroke of the respective cylinders.

Another object of the invention is to provide an engine of the rotating type which is reversible.

Another object of the invention is to provide a novel cam movement for the operation of the exhaust and inlet valves, said cam movement being operable whether the engine is rotating in one direction or another.

Another object of the invention is to provide a novel form of ignition mechanism.

Further objects will hereinafter appear.

The invention consists of the parts and the construction, combination and arrangement of parts as hereinafter more fully described and claimed, having reference to the accompanying drawings, in which—

Figure 1 is a side elevation of the engine.

Fig. 2 is a sectional detail view of the clutch mechanism.

Fig. 3 is a view similar to Fig. 2, showing other parts of the mechanism in section.

Fig. 4 is a detail view of the clutch shifting tube.

Fig. 5 is a side elevation of the engine,

looking at the opposite side from that shown in Fig. 1.

Fig. 6 is a sectional detail view of the starting mechanism.

Fig. 7 is a diagrammatic view of the ignition circuit.

Fig. 8 is a vertical cross section of the engine taken on the line of the inlet valves.

Fig. 9 is a similar section showing the clutch disks and fly-wheel in full and also showing the connecting rods and arms between the pistons and section.

Fig. 10 is a detail view of a portion of the ignition mechanism.

Fig. 11 is a detail view of one of the roller clutches, showing one position thereof.

Fig. 12 is a similar view showing the opposite position of one of the clutch rollers.

Fig. 13 is a detail view of a portion of the central bearing ring showing one of the slots through which the roller clutch tubes extend.

Fig. 14 is a central, vertical, longitudinal section through the engine.

Fig. 15 is a detail view showing the position of the exhaust and inlet valves with relation to their respective cylinders, and also showing the position of the cam rings with relation to the respective valves.

Fig. 16 is a detail sectional view showing the position of the cam rings, with relation to the respective exhaust and inlet valve stems.

Figs. 17, 18 and 19 are diagrammatic views showing the progressive movement of the pistons with relation to the cylinders and the cylinders with relation to the pistons.

Fig. 17 shows the pistons 12 in position to advance when the charge in cylinder 29 is fired. Fig. 18 shows the position of the pistons after the advancement or stroke has been completed, and Fig. 19, the position of the cylinders after advancement. Full line arrows indicate the direction of movement and dotted line arrows, the direction in which both pistons and cylinders are locked against retrograde movement.

Referring to the drawings in detail, and particularly Figs. 8, 9 and 10, A indicates a base plate on which is mounted a pair of standards 2 and 3. Rigidly secured in the upper end of the standard 2 is a hub member 4 and similarly secured in the upper end

of the standard 3 is a hub member 5. Formed on the inner end of each hub member is a clutch disk 6 and extending through the hub members and journaled therein, is a 5 driving shaft 7 upon which is secured a fly-wheel 8.

Journalized on the fly-wheel and centrally thereof is a bearing ring 9 and rigidly secured to said bearing ring are a plurality 10 of piston arms 10, the outer ends of which are T-shaped to form piston rods 11, on the outer ends of which are rigidly secured pistons 12. Formed on the inner end of each hub member 4 and 5 are roller or ball bearings, as indicated at 14, and turnably mounted thereon is a cylinder supporting frame which consists of arms 15, in the outer ends of which are secured double-ended cylinders, as indicated at 16.

20 By referring to Fig. 1, it can be seen that each set of cylinders form a segment of a circle. Further, that the cylinder chambers formed in the respective cylinders are arcular in shape and also that the pistons fitting the same are arcular in shape and rigidly connected by arcuated arms, as indicated at 11. It can further be seen that the cylinders are arranged in circular formation, thereby imparting a fly-wheel appearance 30 to the engine as a whole.

The engine is designed to rotate in either direction, the rotating parts being the cylinders, the pistons, the connecting rods, the centrally disposed bearing ring 9 supporting the same and the fly-wheel 8. A few other parts hereinafter to be mentioned are also adapted to rotate with the cylinders and the pistons but the clutch disk 6 and the standards supporting the same are always 35 stationary, regardless of whether the engine is running in one direction or another.

40 The arms supporting the cylinders 16 are, as previously stated, supported by the roller bearings 14. They are so arranged that four arms, one for each cylinder, are disposed on each side of the clutch disks 6 and the fly-wheel 8. The arms indicated at 15^a are provided with passages 15^b, through which the explosive mixture is conveyed to the 45 cylinders. The arms 15^a are all arranged on one side so that they rotate about the stationary hub member 5. The opposite hub member 4 supports a similar number of arms, indicated at 15^c. These are also provided with central passages, as indicated at 50 15^d, through which the exhaust gases are discharged, as will hereinafter be described.

55 By referring to Fig. 14, it will be seen that each cylinder casting is centrally divided by a head member 17 to form two separate cylinder chambers. Further, that a chamber is formed below each cylinder for the reception of exhaust and inlet valves, as indicated at 18 and 19 respectively, said 60 exhaust valves serving the purpose of open-

ing and closing communication between the cylinders and the passages 15^d formed in the arms 15^c while the inlet valves 19 serve the function of opening and closing communication between the cylinders and the 70 passages 15^b formed in arms 15^a.

75 By referring to Fig. 15, it will be seen that the inlet and exhaust valves are slightly offset with relation to each other. This is resorted to for the purpose of permitting the valve stems supporting the valves, to engage separate cam rings, as will hereinafter be described. The invention shown in the present instance employs four separate cam rings, a pair of inlet valve cam rings on 80 one side of the central bearing ring and a pair of exhaust valve cam rings on the opposite side of the central bearing ring, said cam rings being shown in cross section in Figs. 8, 9 and 14 and in plan view in Fig. 85 15. Cam rings arranged on one side are supported upon outwardly projecting segmental flanges 23 and 24, the flanges 23 forming a part of the piston arms while the flanges 24 form a part of the cylinder supporting arms. The cam rings arranged on the opposite side of the central bearing ring are similarly supported, that is, segmental-shaped projecting flanges 23 and 24 are also formed on this side. The several cam rings 90 are indicated at 25, 26, 27 and 28. All cam rings are so mounted that they may freely turn on their respective segmental bearing supports and they are furthermore freely turnable with relation to each other. They 95 may therefore be termed "floating cam rings" even though they are positively actuated, as will hereinafter be described. The cam ring 25, is provided for the purpose of opening and closing the inlet valves shown 100 in the cylinders indicated at 29, 30, 31 and 32. The cam ring 26 is provided for the purpose of opening and closing the inlet valves disposed in the opposite cylinders indicated at 33, 34, 35 and 36. The cam 110 ring 27 is provided for the purpose of opening and closing the exhaust valves mounted in the cylinders 29, 30, 31 and 32 while the cam ring 28 is provided for the purpose of opening the exhaust valves in the opposite 115 cylinders. In other words, cam rings 25 and 26 will only actuate inlet valves while the cam rings 27 and 28 will only actuate exhaust valves. This arrangement is entirely due to the fact that the incoming mixture is delivered on one side while the exhaust gases are discharged on the opposite side. Hence the arrangement here shown.

120 By referring to Fig. 14 it is seen that four cylinder castings are provided. Further, 125 that said cylinders are centrally divided into separate chambers, thereby providing in all eight cylinders. Sixteen valves are therefore required, there being eight inlet valves, one for each cylinder, and eight exhaust 130

valves, one for each cylinder, each valve being provided with a stem engageable with one or another of the cam rings described, and each valve being normally retained on its seat by means of springs, as indicated at 5 37, said springs being carried by the cylinder supporting arms and being of the flat spring type. This feature does, however, not form any important part of the present 10 invention as coil or other suitable springs might be provided if desired.

The valves are all radially disposed with relation to the center of rotation and are therefore, to a considerable extent, subjected to the centrifugal force produced when 15 the engine is rotating. This is of considerable importance as it materially relieves the respective cam rings of wear. The first cam ring shown in Fig. 14 and indicated 20 by the numeral 25, will only open the inlet valves communicating with the cylinders indicated at 29, 30, 31 and 32. Two of these valves will open in unison and the opposite two will also open in unison. This is of importance 25 as cylinders 29 and 31 receive a charge while cylinders 30 and 32 are firing. The several cam rings employed are identical in construction and the description of one should therefore suffice for all. Each 30 cam ring is provided with a plurality of projecting cams mounted in alignment with the valve stems. These cams have the general shape of the teeth of a ratchet gear, the only difference being that they are spaced 35 apart by flat sections, as indicated at 38, the length of each flat section being equal to the length of a cam and the length of a cam being in turn equal to the circumferential movement of the central bearing ring 40 during the complete stroke of a pair of pistons; that is, an inlet valve, during the suction stroke of its coöperating piston, will begin to open the moment the piston starts its outward movement and it will not close 45 until the piston reaches the end of its outward stroke as each cam is of sufficient length to retain the valve away from its seat until the outward stroke of the piston has been completed. It will therefore drop off 50 the end of the cam which is abrupt as here shown, and will instantly seat itself, the shape of the cams being such that a slow opening of each valve is obtained while an instantaneous closing thereof is secured, 55 this movement being true of both exhaust and inlet valves as the cam rings are identical in shape.

The number of cams employed by each ring depends entirely upon the size of the 60 engine but the length of each cam must in any instance be equal to the circumferential movement of the piston arms on a line parallel with the cam rings. The length of the spaces between the cam projections must 65 also be similar as it is necessary that two in-

let valves remain closed during the firing stroke of their respective cylinders while the opposite two valves open to admit a new charge to the opposite cylinders. The valves are therefore set in such a manner 70 that two are positioned to be engaged by cam projections while the opposite two will merely ride over the intermediate spaces formed between the cam teeth and thus remain closed, this seating of the valves and 75 the relation of the cams thereto being similar in all instances, whether it be the exhaust or the inlet valves.

From the foregoing description it can be seen that means must be provided for turning 80 the cam rings so that the cams carried thereby may pass under the valve stems and thereby raise the same. This movement must also be intermittent as the engine here shown operates on the four-cycle principle. 85 Movement is transmitted to the respective cam rings by the pistons, said movement being transmitted by pawls generally indicated at 40 and 41. The pawls are arranged in pairs on opposite sides of the piston arms, 90 being pivotally mounted on a pin 42 extending therethrough. There are two pawls on each side of a piston arm, the pawls 40 being provided for the purpose of transmitting movement to the cam ring 25 while the 95 pawls 41 are provided for the purpose of transmitting movement to the cam ring 36. The pawls arranged on the opposite side are similar in operation as one set of pawls transmit movement to the ring 27, while 100 the other set of pawls transmit movement to the ring 28.

To more clearly illustrate the movement of the cam rings, the pistons from which the movement is transmitted, and also the movement 105 of the cylinders, it must first be assumed that the engine (see Figs. 14, 17, 18 and 19) is rotating in the direction of arrow *a*. It must further be assumed that the pistons in the cylinders 29, 30, 31 and 32 are 110 also moving in the direction of arrow *a* and that cylinders 29 and 31 are receiving the explosive charge while the cylinders 30 and 32 are firing their charge. It is therefore necessary that the cam ring, during its movement, opens the inlet valves in the cylinders 29 and 31 to permit the charges to be admitted and that the inlet valves in the cylinders 30 and 32 remain closed as the cylinders are firing their charges. The 115 pawls 40 carried by the piston arms will, during the movement of the pistons in the direction of arrow *a*, engage with ratchet teeth 45 formed on the cam ring 25 and thereby turn it in the same direction as the 120 pistons. The cams in register with the inlet valves in the cylinders 29 and 31, will therefore pass under the respective inlet valves and thereby open the same during 125 this movement. The inlet valves in the 130

cylinders 30 and 32 will, however, not be affected by the turning movement of the cam ring as they are in register with the intermediate spaces, and no movement will therefore be transmitted to the same.

- After the pistons have reached the end of their stroke when traveling in the direction of arrow α , it must be assumed that cylinders 29 and 31 have been completely charged 10 with an explosive mixture and that the charges fired in the cylinders 30 and 32 have been completely expanded and burned. It is therefore necessary to compress the charges in the first mentioned cylinders and 15 to exhaust the burned gases in the last named cylinders. This is accomplished by movement of the cylinders in the same direction as arrow α , due to the fact that charges are exploded in other cylinders; for instance, those shown at 34 and 36. The cylinders 29 and 31 will, during this movement, move toward the pistons contained therein and will therefore compress the charges previously admitted; similarly, the cylinders 20 30 and 32 move toward their respective pistons, thus expelling the burned charges. The charges, when compressed in the cylinders 29 and 31, will now be fired, thus causing the pistons in their cylinders to 25 advance in the direction of arrow α . The pistons in the cylinders 30 and 32 will also advance, thereby causing new charges to be admitted to said cylinders, which will be compressed when the charges in the cylinders 30 and 32 are exhausted. The inlet valves in the cylinders 29 and 30 are only 35 opened when the cams formed on the ring 25 are in the right position and only when the ring is turned by means of the pawls 40. The inlet valves contained in the cylinders 33, 34, 35 and 36 are only opened by means 40 of the cams formed on the ring 26 and by referring to Fig. 14 it will be seen that the position of the cams on said ring is directly opposite to the cams formed on ring 25. Further, pawls 41 are reversed with 45 relation to the pawls 40 and will therefore only engage the teeth formed on ring 26. This is of considerable importance as it permits reversal of the engine and equal power production whether the engine is turning in one 50 direction or the other.
- The pawls 40 and 41 are, as previously stated, pivotally mounted. They are normally 55 maintained in engagement with their respective ratchet teeth, which are formed on all cam rings, by means of springs 46 interposed between the upper ends of the pawl arms, as shown in Fig. 14. The pawls 40 will turn the cam ring 25 when the engine is turning in the direction of arrow α , as they engage the abrupt ends of the ratchet teeth associated therewith. They will, however, slide over the ratchet teeth when the 60 engine is turning in the opposite direction.

and will therefore only serve as stop members to secure the cam ring against movement when the engine is turning in the opposite direction.

Suppose that the engine is turning in a direction opposite to that indicated by arrow α . The question might arise as to whether or not the cam ring 25 could operate to lift the inlet valves actuated thereby. The cam ring will operate said inlet valves, due to 70 the fact that it is locked against movement by means of the pawls 40 when the engine is turning in the opposite direction. For instance, movement of the cylinders in a direction opposite to arrow α will cause the 75 stems of the inlet valve to ride over the cams and open the same, due to the fact that the rings are held stationary by the pawls 40. Only two of the valves will open as two valves will be in position to be open 80 while the opposite two valves will be in register with the intermediate spaces between the teeth and will therefore not be open as they will only move from one end of said space to the opposite end. They 85 will then be in readiness to be opened during the next movement of the engine. This is the reason for arranging the cams in one direction on ring 25 and in the opposite direction on ring 26. In other words, when 90 the engine is turning in the direction of arrow α , cam ring 25 will be intermittently turned by means of pawl 40 while cam ring 26 will be secured against movement by means of the pawls 41. Conversely, if reverse movement takes place, pawls 40 will 95 serve as stop members to secure ring 25 against movement while pawls 41 will engage the teeth of the cam ring 26 and thereby alternately move the same.

Hence it can be seen that the engine may rotate in either one direction or another and that this may be accomplished without providing a double-cam arrangement for each set of valves.

When the engine is operating it is understood that it rotates in one direction or another. During said rotation it is obvious that means must be provided for locking the pistons and cylinders against reverse movement; for instance, referring to Fig. 14, if a charge is being fired in the cylinders 30 and 32, it is obvious that the cylinders must be locked against reverse movement the moment the charge is fired so that the 115 pressure created may drive the pistons in the direction of arrow α ; similarly, if charges are fired in the cylinders indicated at 33 and 35, then it is necessary to lock the pistons against reverse movement as the 120 pressure created will in that instance drive the cylinders in the direction of arrow α . Further, it is obvious that if the engine is reversible as far as rotation is concerned, then a locking or clutch mechanism must 125 130

be provided, which is reversible. To accomplish the end desired, I provide a novel form of clutching mechanism known as the "roller clutch," said clutch being clearly 5 illustrated in my patent entitled "Roller clutch," issued March 1, 1919, Patent No. 1,296,345. The roller clutches provided in the present instance are identical to those shown in the patent referred to, the only 10 difference being that they are double in arrangement to permit reversal of the engine and reverse operation of the roller clutches.

By referring to Figs. 8, 9 and 14, it will be seen that I provide two pair of roller 15 clutches on each piston arm; similarly, that I provide two pair of roller clutches on each cylinder supporting arm, the respective 20 roller clutches being shown at 50 and 51. The roller clutches are arranged in alinement, one pair being disposed on each side of the central bearing ring. One roller 25 clutch of each pair is adapted to engage the rim of the fly-wheel 8 while the opposite roller of each pair is adapted to engage the rim of the clutch disks 6, the roller clutches 30 engaging said disks serving the function of locking the pistons and cylinders against retrograde movement when turning in one direction while the roller clutches engaging the face of the fly-wheel rim are provided 35 for the purpose of transmitting the movement of the pistons and cylinders to rotate the fly-wheel and the shaft 7 supporting the same.

35 A more detailed construction of the roller clutches is shown in Figs. 11 and 12. Each roller clutch consists of three rollers, indicated at 52, 53 and 54. All rollers are turnably mounted in a bracket such as shown at 40 55, the rollers 53 and 54 being mounted in slots to permit the same to forcibly engage the fly-wheel rim and the roller 52 when transmitting power to the fly-wheel or to 45 forcibly engage the roller 52 and the clutch disks 6 when locking the pistons and cylinders against retrograde movement. With 50 the clutch rollers assuming the position shown in Fig. 11, it can be seen that the pistons and cylinders can only revolve in the direction of arrow *b*, while the position 55 assumed by the clutch rollers in Fig. 12 will only permit the cylinders and pistons to rotate in the direction of arrow *a*; that is, reverse movement in either instance will be 60 locked as one roller or another will interpose itself between the clutch disk rim and the roller 52 and thereby form a lock.

As previously stated, four roller clutches 65 are mounted in alinement. The two inner roller clutches engaging the fly-wheel rim will always operate in unison while the outside clutches engaging the clutch disks rims will also operate in unison. Further, reverse positions of the respective roller 70 clutches will always be assumed as the inner roller clutches are transmitting power to the fly-wheel rim while the outermost roller clutches are engaging the clutch disks for the purpose of locking the pistons and cylinders against retrograde movement when 75 rotating in a certain direction. If it is desired to reverse the direction of the engine, it is obvious that the position of the respective roller clutches must be changed. Furthermore, that all clutches should be operated in unison as there are eight sets employed in the present instance, there being four separate roller clutches in each set, one pair of each set being arranged on one side of the central bearing ring and another 80 pair on the opposite side, as shown in Figs. 4, 8 and 9.

To quickly and readily change the position of the roller clutches, I provide a laterally movable rod 56 (see Figs. 2, 3 and 4). 85 This rod is tubular in formation (see Fig. 3), and is provided with a series of angularly disposed slots 56', the two innermost slots assuming the same angular position and the two outermost slots a reverse position. Entering the slots formed in the rod 56 are pins 57. These pins form parts of the brackets 55, in which the rollers 52, 53 and 54 of the respective roller clutches are turnably mounted. In other words, lateral 90 movement of a rod 55 in one direction or another will transmit a rocking movement to the coöperating bracket 51, this being due to the fact that the slots into which the pins 57 project, are angularly disposed. 100 There is one rod 56 for each set of roller clutches and all rods are moved inwardly or outwardly in unison as they are in this instance attached to a disk 58 (see Fig. 8), which is slidably mounted on the stationary 105 hub 5, said sliding movement being transmitted thereto by means of a lever 59. Movement of the lever 59 in one direction will throw all the roller clutches into one position which permits the engine to rotate 110 in one direction only while a reverse movement of the lever 59 will transmit movement to all the roller clutches and change their position, thus permitting reversal of 115 the engine.

Each cylinder employed in the present instance is provided with two spark plugs. A circuit is closed through said spark plugs in unison whenever the proper cycle of operation arrives. This is accomplished by means 120 of a mechanism generally indicated in Figs. 5, 7 and 10. The mechanism is provided for making and breaking the respective circuits through the spark plugs at proper time periods and it is actuated by means of a cam 125 ring similar to those previously described, said cam ring being shown at 60. This ring is supported in a manner similar to the other cam rings and is formed integral with ring 28. The cams formed thereon are also 130

similar in shape and in spacing. The circuit breaking and making mechanism is carried by the piston arms 10 and consists of a plate 61 on which is pivotally mounted a rocker 5 arm 62. The lower end of this arm engages the teeth of the cam ring 60 and is intermittently raised and lowered by the same. Secured to the upper portion of the arm 10 is a contact rod 63, on one end of which is formed a downwardly projecting extension 64. Secured to the rocker arm 62 and adapted to engage the extension 64 is a spring arm 65, said arm being only brought into engagement with the extension 64 when the 10 rocker arm is raised by means of one of the cams formed on ring 60. Fig. 7 shows a diagrammatic view of the wiring diagram. In this view it will be seen that the contact rods 63 are disposed on opposite sides of the 15 piston arms and that they are connected by means of a rod or wire 66, the opposite contact rods being directly connected with the spark plugs 67 by means of wires 68. Further, it can be seen that the spark plugs carried by the cylinder directly opposite are also connected in the circuit by means of the wires 69, this double-wiring connection being resorted to to positively insure the closing of a circuit even though one of the 20 rocker arms 62 employed might fail to operate. The rocker arms 62 are always positioned opposite to each other. They furthermore operate in unison, thereby reducing the chances of mis-firing or not firing as 25 the failure of one will be corrected by the operation of the other. For instance, one rocker arm might, under certain conditions, stick or otherwise fail to operate. This would not materially affect the operation of 30 the engine in the present instance as the functioning of one arm would be sufficient to close the circuit through the proper spark plugs. The current may be supplied from any suitable source. One terminal of the 35 circuit is connected with the engine frame while the opposite terminal is connected with an arm 70 on which is mounted a brush engageable with a contact ring 71 secured to the cylinder arms 15^c. A circuit is therefore 40 established whenever a rocker arm is raised into engagement with the projection 64 which forms part of the contact bar 63. Said circuit is, however, not completed until the contact bar engages one or another of a 45 pair of stationary contacts disposed one on each side thereof, as indicated at 72 (see Fig. 10). The contact bar 63 engages one or another of the stationary contacts during the oscillating movement of the cylinders and 50 pistons with relation to each other but the circuit is not completed until the co-operating rocker arm 62 is raised by means of the cam ring 60 and as this does not take place before the piston reaches the end of its 55 stroke, it can readily be seen that complete 60

expansion of one firing charge is permitted before a second or succeeding charge will be fired. This is of great importance in the present instance as it positively insures a complete movement of the cylinders and pistons with relation to each other during each 70 cycle of operation.

By referring to Figs. 8 and 9 it will be seen that the inner ends of the cylinder supporting arms 15^a and 15^c terminate in 75 hub members, each of which is provided with an annular passage communicating with the passages formed in the respective arms. This is also an important feature of the present invention as it permits admission of the combustible mixture from a central point and exhausting of the burned gases through a central connection. Secured on the stationary hub member 15 adjacent the hub from which the cylinder supporting arms 15^a radiate, is a circular casing 80 in which is formed an annular chamber. This casing is stationary but is in constant communication with the annular chamber formed in the adjacent hub by means of 85 ports 81. A carburetor or other suitable gas supplying means may therefore be connected to the casing 80 as this is stationary, hence providing a ready means for supplying the explosive mixture required. Secured on the opposite hub member 4 is a similar casing 82, in which is formed an annular chamber. This casing is adjacent the hub from which the cylinder supporting arms 15^c radiate. The annular chamber formed in the casing is in constant communication with the annular chamber formed in the adjacent hub and therefore permits the exhaust gases discharging 90 through the arms, to enter the chamber in 100 the casing 82. They may be discharged from this casing through an exhaust pipe 83 and can be conveyed to any point desired. By referring to Figs. 8 and 9 it should be obvious that a running joint is 110 formed between the casings 80 and 82 and the respective hub members in which the cylinder supporting arms terminate. A running joint of this nature may be packed, if desired, but as such a construction does 115 not form any material part of the present invention, a showing thereof has been omitted.

In actual operation, if it is desired to start the engine, it may be accomplished 120 by merely rocking the pistons with relation to the cylinders until one or more of the same become charged with an explosive mixture. An extreme rocking movement is then imparted, causing a circuit to be closed 125 and one or more charges to be fired. Rotary movement will then be transmitted and the engine will continue rotating as long as a sufficient supply of explosive mixture is admitted, the speed being regulated 130

- by the quantity and the richness of the mixture supplied. Another method of starting the engine is shown in Fig. 6 in which 85 indicates a cylinder; 86, a piston to which 5 reciprocal movement is transmitted by means of an eccentric 87. This eccentric is freely turnable on the shaft 88, which is driven by an electric motor 89 or any other suitable means. Keyed and slidably mounted on the shaft is a clutch member 90 which may be thrown into or out of engagement with the eccentric 87 whenever it is desired to operate the starting mechanism or 10 the piston mounted therein.
- 15 Formed as a part of the cylinder 85 is a casing in which are formed two passages 91 and 92, the passages 91 and 92 being connected with a carburetor of suitable construction by means of an extension 93. Mounted in the upper end of the cylinder are a pair of check valves 94 and 95 and mounted in passage 91 is a valve 96 which may be opened and closed by means 20 of the clutch operating lever 97.
- 25 The device as a whole is connected with the casing 80 by means of an extension 98 and it operates as follows: If it is desired to start the engine with the starting mechanism shown, it is only necessary to start 30 the motor 89 and to engage the clutch 90 so that reciprocal movement will be transmitted to piston 86 by means of the eccentric 87. Reciprocal movement of the piston will alternately open and close the 35 check valves 94 and 95; in other words, pump in a mixture which is regulated by means of the carburetor. This mixture is delivered through the connection 98 to the casing 80 and passes under pressure from 40 the casing and through the arms 15^a to the cylinders, thus charging the same with an explosive mixture under pressure. The pressure exerted on the mixture by means 45 of the pump or piston 86 will gradually force one or more of the pistons in the cylinders apart until a complete stroke of the same is reached. The electric circuit will thus be closed and the charge fired, thus starting the engine. The clutch 90 50 is immediately released by means of the lever 97; valve 96 is simultaneously raised away from its seat, thus permitting the mixture supplied by the carburetor to pass through the connection 93, passage 92, then 55 by valve 96 and connection 98, into the casing, the admission of the mixture being thereafter controlled by the suction of the respective pistons.
- To thoroughly understand the operation 60 of the engine when revolving in a certain direction; for instance, that indicated by arrow *a* (see Figs. 14, 17, 18 and 19), it is only necessary to assume that all pistons are moved in unison and that all cylinders are moved in unison and that the 65 movement between the pistons and the cylinders is intermittent; that is, all pistons will first advance in the direction of the arrow *a* (see Fig. 17), until their complete stroke has been completed. The cylinders 70 will then move up to the pistons or away from the same, as the case may be (see Fig. 19). They will here stop and the pistons will again move up to or away from their respective cylinders. This movement 75 is the actual operation that takes place, the only difference being that all parts are revolving but the intermittent movement of the cylinders with relation to the pistons takes place during the revolving movement; 80 that is, they are constantly catching up and then running away, with relation to each other when revolving, retrograde movement of the pistons or the cylinders with relation to each other, when a charge is fired being 85 prevented as they are positively locked against reverse movement when revolving in a certain direction, by roller clutches previously described.
- Having thus described my invention, what 90 I claim and desire to secure by Letters Patent is—
1. A rotating internal combustion engine comprising a central stationary bearing support, a plurality of cylinders turnably mounted about said support, a piston carrier also mounted on and turnable about said support, a plurality of pistons secured on said carrier, one for each cylinder, means for admitting a motive fluid to each cylinder and to exhaust it therefrom, a driving shaft extending through the central bearing support, and means for transmitting movement of the cylinders and pistons to rotate the shaft. 100
- 105
2. A rotating internal combustion engine comprising a central stationary bearing support, a plurality of cylinders turnably mounted about said support, a piston carrier also mounted on and turnable about said support, a plurality of pistons secured on said carrier, one for each cylinder, means for admitting a motive fluid to each cylinder and to exhaust it therefrom, means permitting revolving movement of the cylinders and pistons about the stationary bearing support, means to cause the movement of the pistons and cylinders to revolve in either direction, said means preventing retrograde movement of the cylinders and pistons when revolving in either direction, a driving shaft extending through the central bearing support, and means for transmitting the movement of the cylinders and pistons to rotate the shaft. 110
- 115
3. A rotating internal combustion engine comprising a central stationary bearing support, a plurality of cylinders turnably mounted about said support, a piston carrier also mounted on and turnable about said support

- support, a plurality of pistons secured on said carrier, one for each cylinder, an exhaust and an inlet valve mounted in each cylinder, means for delivering an explosive mixture thereto, means for igniting the mixture, inwardly projecting valve stems formed on each valve, a plurality of rings turnably mounted about the central bearing support, one for each set of valves, a plurality of cams on each ring adapted to raise and lower the valves, and means actuated by the pistons for transmitting movement to the rings.
4. A rotating internal combustion engine comprising a central stationary bearing support, a plurality of cylinders turnably mounted about said support, a shaft journaled in and extending through said central bearing support, a fly-wheel secured on said shaft, a piston carrier journaled on the fly-wheel and turnable thereabout, a plurality of pistons supported by the carrier, one for each cylinder, a clutch disk disposed on each side of the fly-wheel and secured with relation to the central bearing support, and a plurality of clutch rollers carried by the cylinders and the piston carrier engageable with the fly-wheel and the clutch disks, said clutch rollers adapted to transmit the movement of the cylinders and the pistons to rotate the fly-wheel and the shaft supporting the same.
5. A rotating internal combustion engine comprising a central stationary bearing support, a plurality of cylinders turnably mounted about said support, a shaft journaled in and extending through said central bearing support, a fly-wheel secured on said shaft, a piston carrier journaled on the fly-wheel and turnable thereabout, a plurality of pistons supported by the carrier, one for each cylinder, and means permitting revolving movement of the cylinders and pistons, means to cause the movement of the pistons and cylinders to revolve in either direction, said means adapted to transmit the movement of the pistons and cylinders to rotate the fly-wheel and the shaft supporting the same.
6. A rotating internal combustion engine comprising a central stationary bearing support, a plurality of cylinders turnably mounted about said support, a shaft journaled in and extending through said central bearing support, a fly-wheel secured on said shaft, a piston carrier journaled on the fly-wheel and turnable thereabout, a plurality of pistons supported by the carrier, one for each cylinder, means permitting revolving movement of the cylinders and pistons, means to cause the movement of the pistons and cylinders to revolve in either direction, said means adapted to transmit the movement of the pistons and cylinders to rotate the fly-wheel and the shaft supporting the same, and a pair of stationary clutch disks secured to the central bearing support, one on each side of the fly-wheel, said disks adapted to cooperate with the cylinder and piston power-transmitting means to lock the cylinders and the pistons against retrograde movement when revolving in either direction.
7. A rotating internal combustion engine comprising a central stationary bearing support, a plurality of cylinders turnably mounted about said support, a shaft journaled in and extending through said central bearing support, a fly-wheel secured on said shaft, a piston carrier journaled on the fly-wheel and turnable thereabout, a plurality of pistons supported by the carrier, one for each cylinder, a clutch disk disposed on each side of the fly-wheel and secured with relation to the central bearing support, and a plurality of clutch rollers carried by the cylinders and the piston carrier engageable with the fly-wheel and the clutch disks, said clutch rollers adapted to transmit the movement of the cylinders and the pistons to rotate the fly-wheel and the shaft supporting the same.
8. A rotating internal combustion engine comprising a central stationary bearing support, a plurality of cylinders turnably mounted about said support, a shaft journaled in and extending through said central bearing support, a fly-wheel secured on said shaft, a piston carrier journaled on the fly-wheel and turnable thereabout, a plurality of pistons supported by the carrier, one for each cylinder, a clutch disk disposed on each side of the fly-wheel and secured with relation to the central bearing support, and a plurality of double acting reversible clutch rollers carried by the cylinders and by the piston carrier, said rollers being engageable with the clutch disks and the fly-wheel to transmit the movement of the pistons and the cylinders to rotate the fly-wheel and the shaft supported thereby in either direction and to lock the cylinders and the pistons against retrograde movement when reyoving in either direction.
9. A rotating internal combustion engine comprising a central stationary bearing support, a plurality of cylinders turnably mounted about said support, a shaft journaled in and extending through said central bearing support, a fly-wheel secured on said shaft, a piston carrier journaled on the fly-wheel and turnable thereabout, a plurality of pistons supported by the carrier, one for each cylinder, a clutch disk disposed on each side of the fly-wheel and secured with relation to the central bearing support, a plurality of double acting reversible clutch rollers carried by the cylinders and by the piston carrier, said rollers being engageable with the clutch disks and the fly-wheel to transmit the movement of the pistons and the cylinders to rotate the fly-wheel and the shaft supported thereby in either direction and to lock the cylinders and the pistons

against retrograde movement when revolving in either direction, and manually operated means for reversing the position of the double acting clutch rollers to permit reversal of the engine.

10. A rotating internal combustion engine comprising a central stationary bearing support, a plurality of cylinders turnably mounted about said support, a shaft journaled in and extending through said central bearing support, a fly-wheel secured on said shaft, a piston carrier journaled on the fly-wheel and turnable thereabout, a plurality of pistons supported by the carrier, one for each cylinder, a clutch disk disposed on each side of the fly-wheel and secured with relation to the central bearing support, a plurality of double acting reversible clutch rollers carried by the cylinders and by the piston carrier, said rollers being engageable with the clutch disks and the fly-wheel to transmit the movement of the pistons and cylinders to rotate the fly-wheel and the shaft supported thereby in either direction and to lock the cylinders and the pistons against retrograde movement when revolving in either direction, and manually operated means reversing the position of all the double acting clutch rollers in unison to permit reversal of the engine.

11. A rotating internal combustion engine comprising a central stationary bearing support, a plurality of cylinders turnably mounted about said support, a shaft journaled in and extending through said central bearing support, a fly-wheel secured on said shaft, a piston carrier journaled on the fly-wheel and turnable thereabout, a plurality of pistons supported by the carrier, one for each cylinder, an inlet and an exhaust valve communicating with each cylinder, an inwardly projecting valve stem attached to each valve, a plurality of rings supported by the piston carrier and freely turnable thereon, one ring for each set of valves, cam members on each ring engageable with the valve stems to open and close the valves, and means actuated by the movement of the piston carrier for transmitting a turning movement to the respective rings.

12. A rotating internal combustion engine comprising a central stationary bearing support, a plurality of cylinders turnably mounted about said support, a shaft journaled in and extending through said central bearing support, a fly-wheel secured on said shaft, a piston carrier journaled on the fly-wheel and turnable thereabout, a plurality of pistons supported by the carrier, one for each cylinder, an inlet and an exhaust valve communicating with each cylinder, an inwardly projecting valve stem attached to each valve, a plurality of rings supported by the piston carrier and freely turnable

thereon, one ring for each set of valves, cam members on each ring engageable with the valve stems to open and close the valves, means actuated by the movement of the piston carrier for transmitting a turning movement to the respective rings, said means comprising spring-actuated pawls carried by the piston carrier, and ratchet teeth formed on each ring with which said pawls are adapted to engage.

13. A rotating internal combustion engine comprising a central stationary bearing support, a plurality of cylinders turnably mounted about said support, a shaft journaled in and extending through said central bearing support, a fly-wheel secured on said shaft, a piston carrier journaled on the fly-wheel and turnable thereabout, a plurality of pistons supported by the carrier, one for each cylinder, an inlet and an exhaust valve communicating with each cylinder, an inwardly projecting valve stem attached to each valve, a plurality of rings supported by the piston carrier and freely turnable thereon, one ring for each set of valves, cam members on each ring engageable with the valve stems to open and close the valves, means actuated by the movement of the piston carrier for transmitting a turning movement to the respective rings, said means comprising spring-actuated pawls carried by the piston carrier, ratchet teeth formed on each ring with which said pawls are adapted to engage, a pair of spark plugs in each cylinder, a cam ring supported by and turnably mounted on the piston carrier, and means actuated by said last named cam ring for making or breaking the circuit through the spark plugs.

14. In an engine of the character described, the combination with a piston carrier and the cylinders, of an inlet valve and an exhaust valve carried by and communicating with each cylinder, a ring for each set of valves carried by and turnably mounted on the piston carrier, cam members on each ring adapted to open and close the respective valves, and means on the piston carrier adapted to alternately transmit a turning movement to the rings.

15. In an engine of the character described, the combination with a piston carrier and the cylinders, of an inlet valve and an exhaust valve carried by and communicating with each cylinder, a ring for each set of valves carried by and turnably mounted on the piston carrier, cam members on each ring adapted to open and close the respective valves, a pair of spring-actuated pawl members pivotally mounted on the piston carrier, and ratchet teeth on the respective rings with which the pawls are engageable to intermittently transmit a turning movement to each ring.

16. In an engine of the character described, the combination with the piston carrier and the cylinders, of a pair of spark plugs mounted in each cylinder, a ring supported by and turnably mounted on the piston carrier, a plurality of cams formed on said ring, a rocker arm supported on the piston carrier and engageable with the cam members on the ring, said rocker arm adapted to be raised and lowered by the cams, and means actuated by said movement of the rocker arm for making or breaking a circuit through the spark plugs. 65
17. A rotating internal combustion engine comprising a central stationary bearing support, a plurality of cylinders arranged to rotate about said support, hub members journaled and turnable about said support, arms radiating from said hub members to support the cylinders, a shaft extending through the bearing support and journaled therein, a fly-wheel secured on the said shaft and turnable therewith, a piston carrier journaled upon the fly-wheel and turnable thereabout, a plurality of pistons secured to said carrier, one for each cylinder, passages formed in the cylinder supporting arms and the hubs to which they are attached, and means coöperating therewith for admitting 70 and exhausting a motive fluid to each cylinder. 75
18. A rotating internal combustion engine comprising a central stationary bearing support, a plurality of cylinders arranged to rotate about said support, hub members journaled and turnable about said support, arms radiating from said hub members to support the cylinders, a shaft extending through the bearing support and journaled therein, a fly-wheel secured on the said shaft and turnable therewith, a piston carrier journaled upon the fly-wheel and turnable thereabout, a plurality of pistons secured to said carrier, one for each cylinder, an inlet 80 and an exhaust valve communicating with each cylinder, a cam ring for each set of valves supported by and turnable about the piston carrier, means on the piston carrier for transmitting an intermittent movement to said cam rings to open and close said valves, passages formed in the cylinder supporting arms communicating with the valves and the cylinders, and means coöperating 85 with said arms for delivering an explosive mixture. 90
19. A rotating internal combustion engine comprising a central stationary bearing support, a plurality of cylinders arranged to rotate about said support, hub members journaled and turnable about said support, arms radiating from said hub members to support the cylinders, a shaft extending through the bearing support and journaled therein, a fly-wheel secured on the said shaft and turnable therewith, a piston carrier journaled upon the fly-wheel and turnable thereabout, a plurality of pistons secured to said carrier, one for each cylinder, an inlet and an exhaust valve communicating with each cylinder, a cam ring for each set of valves supported by and turnable about the piston carrier, means on the piston carrier for transmitting an intermittent movement to said cam rings to open and close said valves, passages formed in the cylinder supporting arms communicating with the valves and the cylinders, and means coöperating with said arms for delivering an explosive mixture. 100
20. A rotating internal combustion engine comprising a central stationary bearing support, a plurality of cylinders arranged to rotate about said support, hub members journaled and turnable about said support, arms radiating from said hub members to support the cylinders, a shaft extending through the bearing support and journaled therein, a fly-wheel secured on the said shaft and turnable therewith, a piston carrier journaled upon the fly-wheel and turnable thereabout, a plurality of pistons secured to said carrier, one for each cylinder, an inlet and an exhaust valve communicating with each cylinder, a cam ring for each set of valves supported by and turnable about the piston carrier, means on the piston carrier for transmitting an intermittent movement to said cam rings to open and close said valves, passages formed in the cylinder supporting arms communicating with the valves and the cylinders, and means coöperating with said arms for delivering an explosive mixture. 105
21. In an engine of the character described, the combination with the fly-wheel, the piston carrier and the cylinders, of a stationary clutch disk arranged on each side of the fly-wheel, and means interposed between the cylinders and the piston carrier on one side and the fly-wheel and clutch disks on the other side for transmitting movement of the cylinders to the fly-wheel regardless of either direction of rotation, said means also adapted to lock the cylinders and the piston carrier. 110

- ders and piston carrier against retrograde movement regardless of the direction of rotation of the same.
22. In an engine of the character described, the combination with the fly-wheel, the piston carrier and the cylinders, of a stationary clutch disk arranged on each side of the fly-wheel, means interposed between the cylinders and the piston carrier on one side and the fly-wheel and clutch disks on the other side for transmitting movement of the cylinders to the fly-wheel regardless of either direction of rotation, said means also adapted to lock the cylinders and piston carrier against retrograde movement regardless of the direction of rotation of the same, said means comprising a plurality of sets of double acting clutch rollers, said clutch rollers engaging the surface of the fly-wheel and the surface of the clutch disks, and means for reversing the position of all the clutch rollers in unison.

23. A rotating internal combustion engine comprising a central stationary bearing support, a plurality of cylinders turnably mounted about said support, a piston carrier also mounted on and turnable about said support, a plurality of pistons secured on said carrier, one for each cylinder, said pistons revolving in unison and said cylinders revolving in unison, said pistons having a lagging and forward movement during their continuous rotation with respect to the rotating movement of the cylinders, and means for admitting a motive fluid to each cylinder and to exhaust it therefrom.

In testimony whereof I have hereunto set my hand in the presence of two subscribing witnesses.
